MEANS FOR SELECTING RADIO PROGRAMS

Russell C. Lane, Dayton, Ohio, assignor, by mesne assignments, to Radio Corporation of America, New York, N. Y., a corporation of Delaware

Application December 30, 1931, Serial No. 583,899

6 Claims. (Cl. 250—20)

This invention relates to mechanism preselecting a radio program for an extended interval of time and thence controlling a radio instrument strictly in accordance with the program preselected.

The vast number of radio broadcasting stations that may be found on the air, and the vast range of features that go to make up the broadcasting program of each station, confronts the radio listener with a problem as to what ones of the available numbers to be gathered from the multitude of broadcast stations he will enjoy or even care to hear. Each of these station programs will probably vary in character and order of dissemination so as to include lectures, 10 dramas, news items, operas, jazz or single installments of some continued program at irregular intervals for a stated period. Certain ones of these numbers on each program, the radio listener will desire to listen to, others he will not care about, still others he will not be able to tolerate. It therefore becomes desirable that the 15 listener may be able to determine beforehand the particular features of the evening's radio program and thence provide for the control of his 20 radio set during the evening in strict accordance with the program he has selected or determined 25 to listen to.

The present invention provides means whereby the radio listener may prepare, or have prepared, a control web that will bear indicia characteristic of each station's particular program number that the listener desires to enjoy, and thence start the selector mechanism into operation and forget about it until he desires to use 30 his radio set at some subsequent time. By the apparatus here disclosed the listener may spend a few minutes at a single instance in selecting the desired program for a stated period before the selected program is to commence, and then 35 leave the rest to the selector mechanism, as compared with the usual practice of attending the receiver frequently during the evening's entertainment to make the various desired tunings.

The features of the station program selected 40 may be miscellaneous in character, representing the choice bits of all that the evening's program may afford, for the features selected may be generally classifiable under one or more general heads. That is to say, the listener may desire 45 to have his evening's program made up entirely of dance music. He may have a particular weakness for jazz. On the other hand, he may care 50 to tolerate nothing but the operas and classical 55 music. Whatever the desires of the evening's

program may amount to, the radio listener has only to look over the printed programs as to what the various stations will broadcast, decide upon the numbers he prefers to listen to, and thence prepare the record web in accordance with 5 the arbitrary program he has selected.

As a further aid, and to save the valuable time of a busy man, a structure of the type herein disclosed lends itself to the method of program selection wherein an editing agency will study 10 and analyze all of the radio station broadcast programs within any certain locality, and then classify the features of the various station programs analyzed into characteristic groups and arranging the several station features under each 15 characteristic group according to their order of time. The editing agency will then prepare the control elements or webs so as to bear proper indicia of each station broadcast and its time of contribution to the program of the selected character. The prepared control elements are then 20 ready for distribution to subscribers, or as may otherwise have been provided for, and the radio listener or subscriber upon receipt of the control element places it in his instrument and gives 25 the same an initial start, after which he need pay no more attention to the adjustment of his radio instrument for his evening's entertainment.

Accordingly, one of the objects of the invention is to provide a record controlled means for 30 setting and resetting a radio instrument according to the predetermined desires of an attendant.

A further object of the invention is to provide 35 a device that will control a radio instrument from a prepared program strip.

A further object of the invention is to provide 40 a control for a radio instrument according to a miscellaneous program in which the contributing features may be selected from a plurality of broadcasting stations.

A further object of the invention is to provide 45 for the control of a radio program over an extended period requiring the least attention of a personal attendant.

A further object of the invention is to provide 50 a radio instrument controlling means that will respond to all of the variations of record preparation.

A further object of the invention is to provide 55 a radio instrument controlling means whose fidelity of operation will not be materially interfered with by variations of dimensions in record sheet manufacture.

A further object of the invention is to provide 60 means for disengaging the driving relation of the 55

control sheet, or otherwise rendering the control mechanism non-operative.

Still other objects include means for automatically interrupting the record driving motion at the termination of a record sheet, or at the manifestation of certain other conditions.

A still further object of the invention is to provide means for driving an edited program record strip for controlling the settings of a radio instrument.

Further objects and advantages of the present invention will be apparent from the following description, reference being had to the accompanying drawings, wherein a preferred embodiment of one form of the present invention is clearly shown.

In the drawings:

Fig. 1 is a side elevation of a preselector mechanism constructed in accordance with the present invention, a portion of the enclosing case having been moved to an open position so as to disclose certain elements of structure.

Fig. 2 is a vertical sectional view of the apparatus substantially as indicated by the line and arrows 2-2 of Fig. 1.

Fig. 3 is a sectional view of the device, being substantially indicated by the line and arrows 3-3 of Fig. 2.

Fig. 4 is a transverse sectional view of a portion of the mechanism substantially as indicated by the line and arrows 4-4 of Fig. 2 illustrating the relation of certain features of the invention.

Fig. 5 is a plan view of the station selector mechanism substantially as is indicated by the line and arrows 5-5 of Fig. 2.

Fig. 6 is a detail of construction substantially as indicated by the line and arrow 6-6 of Fig. 1.

Fig. 7 is a fragmentary view of certain portions shown in section substantially as indicated by the line and arrow 7-7 of Fig. 6.

Fig. 8 is a detail of the record preparing means, and is substantially that view indicated by the line and arrows 8-8 of Fig. 1.

Fig. 9 is an enlarged detail illustrating the cooperation of the contributing parts in actuating the station call mechanism.

Fig. 10 is a diagrammatic illustration of the circuit arrangement.

Fig. 11 is a view of a plurality of edited program webs or strips.

In accomplishing the foregoing objects, the hereinafter described structure has been provided and consists essentially of a casing A enclosing a frame work B that supports the mechanism C for driving a control element D or the like carrying provisions for actuating a station call mechanism E that preferably has electrical communication with instrument adjusting means M operatively connected with a radio receiver R, and which adjusting means may correspond to that of my copending application Serial No. 550,179 filed July 11, 1931.

Referring particularly to the drawings, the casing A provides a face member 20 and side members 21, 22 joined by a back member 23 and all mounted upon a base 24, the side member 22 preferably being hinged at 25 and provided with a latch mechanism at 26 for holding the panel in place. A bead, molding or other finishing strip 27 lies over the meeting edge of the sides 21 and 22 and is cut away as at 28 to provide clearance for the said side 22 whenever it is pivoted about its hinge 25. In the preferred form the base 24 is of skeleton or rail construction so as to provide

an opening therein sufficient for manipulation of parts as occasion may demand.

Upon the base 24 there is mounted, by means of the screws 30, the frame work B hereinbefore referred to, and the frame work provides upright members 31 and 32 that carry bearings 33 and 34 for a record supply spool 35, and bearings 36 and 37 for a take-up spool 38. Other elements of the frame structure as the pedestal 40 provides a bearing 41 to journal a shaft 42 of a rotatable drum 43, and may also include a bracket 44 affixed to the frame as at 45 with provisions for engaging about a clock or motor 46, and providing a bearing 47 in line with the bearing 41, which bracket is then affixed to a rail 48 of the case A by screws or similar devices 49. This construction makes for the mounting of the clock or motor 46 so as to dispose its face 49 in an aperture 50 of the front panel 20 where it may perform the usual functions of a time piece.

An incrementally adjustable connection between the shaft 42 of the driving drum and the power shaft or minute shaft 51 or the driving mechanism is provided as shown. To accomplish this the hub 52 of the driving drum is provided with a key way 53 to receive a pin or key 54 carried by the shaft 42, and the mating end of the shaft 42 is provided with a head 55 having a conical recess 56 for engagement with the knurled head 57 of the minute shaft 51. Behind the head 55 is placed a washer 58 against which is seated a spring 59 having its other end engaging the bracket 44 about the bearing 47, and continually urging the head 55 of the shaft 42 into engagement with the minute shaft 51 of the driving means. Thus a driving connection is provided between the driving means 46 and the drum 43, and provision is made by means of the slot and pin engagement 53, 54 by which the relation of the drum to that of the minute shaft may be varied. An aperture 60 through the back 23 of the case allows for the projection of the shaft 42 to the exterior of the case where a control knob 61 may be applied. Provision is also made by this structure for the setting of the clockwork or motor according to a standard of time, and for correcting the setting according to the standard should such occasion arise. To facilitate this, the face 49 carries the usual time markings and forms a scale indicative of the movement of the hands 62.

The record supply spool 35 is provided with a removable shaft 65, which has a non-rounded portion 66 that makes a driving connection with the hub 67 of said spool and thereby has provision for mounting in the bearings 33 and 34 of the frame as hereinbefore described. The member 32 of the frame carries a spring detent 68 that seats in an annular groove 69 carried by the shaft 65 and operates to hold the shaft 65, and the spool 35 in properly assembled relation with respect to the bearings in the frame, and yet makes provision for withdrawal of the shaft and removal of the spool for replacement with another, or for rewinding with a new supply of record web D. For this purpose a control knob 70 is attached to the other end of the shaft 65 after it projects through an aperture 71 of the casing member 23.

To remove the supply spool the shaft 65 is withdrawn from the case and spool, whereupon the spool may be removed through the bottom of the case. In replacing a new spool the lugs 33a and 34a disposed about the bearings 33 and 34 respectively will guide the spool for proper alignment 75

so that the shaft 65 may be readily inserted to hold it in place. The non-rounded provisions 66 of the shaft that mate up with the spool 35 make it possible to rotate the same in either direction by the knob 70 from without the case. In order to take up the slack in the feed of the record a light leaf spring member 12 is secured to the bearing 33 so as to have a plurality of arms or other tensioning means engaging the end member of the spool 35. The spring tension of the member 12 is just sufficient to hold the spool in the angular position to which it has been rotated but will not materially interfere or resist the driving of the web D when the device is in operation.

As before stated, the take-up spool 38 is journaled in bearings 36 and 37 provided by the frame member. This spool is somewhat different in construction from that of the supply spool, it comprising a pair of flanged head members 13 fixed to a stub shaft 14 that are held in spaced relation by a cylindrical portion 15 to support the exhausted end of the web D. Provision is made for attaching the web D to the pick-up spool by cutting apertures or slits 16 through the flanges of the head member 13 and just outside of the cylindrical portion 15, within which slits there is disposed a spring bar 11 so as to lay against the surface of the cylinder 15. Attachment is made by withdrawing the bar 11 from without one of the slots, placing the end of the web between the bar and the cylinder and thence reinserting the end of the bar in the slot 16.

Means are provided for winding up the exhausted portion of the web by a novel spring urged connection between the spool and a control shaft 18 that includes the detail of construction illustrated in Fig. 7. In that instance the control shaft 18 is fitted within the bearing 37 and carries an axial bore 19 to form a journal for the extreme end of the shaft 14. A terminating flange 80 of the shaft 18 provides a thrust bearing between the frame member 32 and the adjacent head 13 of the spool and likewise provides means for anchoring the end of a spiral spring 81 that is coiled about the flange and has its opposite end secured to a lug 82 carried by the head member 13. The relation of the bearing engagements between the shaft 18 in the bearing 37 and between the shaft 14 and the sleeve portion 18 are such that the spring tension that may be stored up in the spring 81 will operate to drive the spool 38 relative to the shaft 18 but will not allow rotation of the shaft 18 relative to the bearing 37 by any amount of spring energy that may be stored up in the element 81. The shaft 18 is extended to project through the back member 23 of the case where it is fitted with a control knob 83 by which the shaft 18 may be rotated for storing up tension in the spring 81 for a purpose that will presently appear.

By reference to Fig. 2 of the drawings, it will be observed that the structure thus far described provides for the continuous movement of a web or paper strip carried by the supply spool 35 trained over the drum 43 and whose exhausted end is attached to the take-up spool 38, the drum 43 being driven at a substantially constant rate of speed by the motor or clockwork 46. To facilitate in this the drum 43 may have its cylindrical surface 85 roughened sufficiently to increase the frictional engagement between the web and the said drum so as to prevent substantial slipping thereof as the drum is rotated and the web is drawn from a supply spool 35. The drum also

carries marginal flanges 86 that operate as guides for the web so that the same will properly track with respect to the station selector mechanism E, soon to be described. In the present embodiment the shell 85 of the drum constitutes a common electrical connection for the individual elements of the station selector mechanism and operates when engaged by the said elements to complete circuits therethrough. The web D that is trained over the drum and passes between it and the station selector mechanism E, normally insulates the elements of that mechanism from the drum, but due to specific selected preparations of the web may allow engagement of desired ones of the elements of the station selector mechanism and contact therewith so as to complete the desired circuits. In the present embodiment as illustrated the web D is prepared by the punch mechanism F as will presently appear.

As before stated the station selector mechanism E is mounted upon the movable panel 22 that has a latching engagement with the main portion of the case, and the said mechanism constitutes a plurality of spring leaf conductors 90 individually and insulatingly mounted upon a block of insulation 91 by means of the screws or similar devices 92 and 93. The contact elements 90, as they may be defined, may be somewhat bowed in form so as to engage the web D and the shell 85 of the drum under certain conditions when the panel 22 is latched into place, and each of the elements 90 carries a contact roller 94 adapted to roll over the web D or the drum 43, as the case may be. The elements 90 are of such character that they will engage the web or cylinder when the panel 22 is moved into place before the same is depressed into its latched position, and the subsequent movement of the panel to latch the same tends to straighten out or flex the elements 90 somewhat so that the web will be engaged firmly by the rollers 94 and will thereby firmly engage the surface of the drum at that point, which facilitates driving of the web by the drum 43.

To each of the contact elements 90 is attached a lead 95 and they are gathered in a multi-conductor cable and thence attached to the instrument adjusting mechanism within the radio receiver or otherwise disposed thereabout. To this multi-conductor cable is also added a lead forming the common connection with the drum 43, as well as leads that are specific to a release mechanism for the latch 26. It is desired that the station selector mechanism E provide a contact element 90 for each station to which the instrument is to be tuned, and two or more additional contact elements for the control of other functions. In the illustrated embodiment one of these additional elements is for a stop and start mechanism, while the second is designed to operate a release mechanism carried by the selector unit itself. If it be so desired other elements may be added to the selector mechanism specific to the various functions desired. The particular adaptation of these additional elements will follow in a later paragraph.

After the web D is trained over the drum 43 and passes the selector mechanism E it passes over a table portion or platen 100 that constitutes a record preparing station and cooperates with the record preparing means F to prepare the web D so that it will control the radio instrument according to the desires of the attendant. The record preparing means embodies a die member 101 extending across the table 100 and that carries a series of apertures 102 75

aligned with the rollers 94 of the contact elements 90. Spaced slightly above the die member 101 there is a detent bar 103 supporting a channel member 104 and enclosing a slidable carriage 105, housing a spring 106 and a punch member 107. The detent bar is spaced above the die member 101 to allow the unrestricted passage of the web D therebetween and is apertured at 108 in strict alignment with the apertures 102 of the die member. Adjacent each of the apertures 108 there is a detent recess 109 that cooperates with a rib 110 carried by the lower end of the carriage 105 for locating the same with respect to the apertures 102 and 108, 15 and the lower end of the carriage 105 provides a sleeve like bearing 111 to confine the lower end of the spring 106 and to guide the lower end of the punch 107.

This construction makes provision for movement of the carriage 105 with its punch 107 throughout the extent of the detent bar 103, the rib 110 successively falling into the recesses 109 as the carriage is thus moved. When the carriage is moved along the channel member 104 to any one of the positions in which the rib 110 will be seated in the recess 109 the punch 107 will then be in strict alignment with the apertures 108 and 102, and should the punch 107 then be depressed against the spring 106, the punch will then operate to cut out a portion of the web D that lies over the adjacent one of the apertures 102 of the die member. Since the apertures 102 are in alignment with the contact elements 90, the aperture that is thus prepared when it is allowed to pass over the drum between it and the contact element 90 will allow the roller 94 to fall therethrough and engage the surface of the drum whereby an electrical circuit is completed. As illustrated in Fig. 2, the frame member B provides a chamber 115 that receives a drawer or receptacle 116 that operates to receive the particles of the web D as they are punched out.

To facilitate in punching the web D in accordance with any desired sequence of stations to be listened to, a station scale 120 has been affixed in close proximity to the record preparation means and bears the proper indicia designating the stations or other functions for which the web is to be prepared. In the illustrated embodiment as appears in Fig. 1, this station scale 120 is prepared with the indicia 121 including the indicia S-S, A, B, C, D, E, F, G, H, I and R. Of these indicia S-S relates to a stop start mechanism which in the preferred form is a step mechanism operating at alternate actuations to energize and deenergize the instrument, but it is clearly obvious that instead of having a single contact element 90 to perform both functions that the contact elements may be duplicated where it is desired to energize and deenergize the set by separate mechanisms. The indicia A to I inclusive have reference to particular station settings and constitute the call letters of those broadcast stations that are more frequently listened to. The indicia R is indicative of a release mechanism for which the sheet may be prepared or not as is desired. It has reference to the release mechanism by which the station selector mechanism is lifted from its engagement with the drum C or the driving of the web otherwise interrupted.

The station scale thus affixed is to aid in preparing the web D according to the functions that it is to control. A second scale 125 is secured

to any convenient portion of the structure and is graduated in time substantially as indicated in Fig. 1. As here illustrated a zero point on the scale 125 is affixed opposite the line of apertures 108 and is thence graduated along the edge extending away from the punch mechanism and toward the take-up spool 38 in five minute intervals of time, and this scale is indicative of the rate of travel of the web as it is driven by the clock or motor 46, the numerals 1, 2, 3 10 15 and the thereto applied indicating hours of time. The time scale 125 also carries an index arrow designated P that is situated in line with the point of pick-up or engagement between the station selector mechanism E and the drum C, and from thence extends upwardly and may follow the contour of the flange 86 of the drum which portion thereof is graduated in time as is the lower portion.

According to the structure of the disclosure 20 thus far, the attendant or the radio listener may, after the panel 22 has been unlatched and moved outwardly so as to give access to the mechanism F, then draw a portion of the web D from the supply spool passing it through the punch mechanism so that it may be attached to the take-up spool 38. The carriage 105 may then be moved along the channel member 104 until the punch 107 is opposite the indicia S-S whereupon it will be operated to punch a hole in the web D. With 30 the web retained in that position the attendant next moves the carriage 105 along the scale 120 until it is opposite to one of the markings A to I inclusive, corresponding to the first station that he desires the instrument to be tuned to, 35 and thence reoperates the punch 107 to punch a hole in the web D at that point. He next moves the web D through the punch mechanism and towards the take-up spool a distance equivalent to the time interval that he proposes to listen 40 to the first station selected. When that has been accomplished he moves the carriage 105 along the scale 120 until it is adjusted opposite the station marking that is next in order of the selection he has made, whereupon he operates the punch 45 mechanism to prepare the web D in accordance with that program number selected. This same procedure is followed out in preparing the web D for the remaining portion of the program, with a final preparation of the web D at a selected interval of time after the last station selected, 50 when he proposes to turn off his instrument. This last punching will be made at the point S-S on the scale and when presented in its regular sequence will operate to deenergize the instrument. 55

For a practical application of this system, let it be assumed that the attendant, after looking over the current program of radio broadcast as printed in a local newspaper or other periodical or the like, decides that he wishes to make up his evening's entertainment from station G that will broadcast a desirable number from 3:30 to 4 P. M.; from station E from 4:00 to 5:00; from station G again from 5:00 to 6 P. M. For the period beginning at 6:00 and ending at 7:30, there appears to be nothing that he is particularly interested in, but from 7:30 to 8:30 he desires to listen to the station H; and thence from 8:30 to 9:00, station A; from 9:00 to 9:30 station B; and from 9:30 to 10:00 he desires to return to station A and at 10:00 desires to shut off the instrument.

As indicated hereinabove, and to prepare the web D to control the setting of the radio instru- 75

ment throughout the evening in accordance with the particular station broadcast that he has determined upon, the web while it is in the position indicated after first being drawn through the punch mechanism with a sufficient end to attach to the take-up spool is punched at the point S—S on the scale 120 with the aperture 130 for the start preparation, and is then punched opposite the point G at 131 indicative of the first station that is to be tuned in. The web D is thence moved along the scale 125 equivalent to a half hour interval of time, or in this instance the interval of time between the beginning of the desired feature to be broadcast by the station G and that to be broadcast by that station E. With the web maintained in that position the punch is moved to a position opposite the marking E on the scale 120 and is operated to punch the web at the point 132. According to the desired schedule of tuning it is proposed to return to the station G at 5 o'clock, or after one hour from the time that the program of station E is to be tuned in, therefore the punch 107 is moved to a point opposite the station marking G of the scale 120 where it is again operated to prepare the web with an aperture 133 in accordance with that station setting.

This procedure is continued until the web D is prepared in accordance with the sequence of station broadcasts that have been determined. This record preparation may amount to a continuous program for the afternoon and evening, or it may include silent periods, an instance of which is indicated by the foregoing evening's schedule. The only difference in web preparation where that preparation is to include a silent period is to add an additional web preparation opposite the scale indicia S—S to mark the stopping of the set, and a second preparation at the end of the silent period and coincident in time with the next succeeding station preparation so as to reenergize the instrument. The web preparation in accordance with the foregoing example of evening's tuning is fully illustrated in Fig. 1 of the drawings, where the apertures 130 to 140 inclusive have been plotted upon the illustrated web D in strict accordance with the determined sequence. While the web is illustrated as having the crossed lines X and Y, they are not in fact applied to the web, but are here used only for the purposes of aiding in plotting the various station preparations. At the conclusion of the web preparation, the prepared web is trained back over the drum C and adjusted such that the first or start preparation 130 is opposite to a mark on the upper portion of the scale 125, equivalent to the interval of time between that at which the preselector is to be started and the time at which the first station is to be called up. To illustrate this, assume that the web is prepared and that fifteen minutes will elapse before the station G is to be tuned in. The web is so adjusted with respect to the scale 125 that the start aperture 130 will be opposite the fifteen minute mark above the point P.

This having been done the movable panel 22 is moved into place where it is held by the latch 26. The station selector mechanism E will then be in engagement with the prepared web D and will provide sufficient frictional engagement between the web D and the drum and rollers of the contact elements to cause the web D to be driven by the said drum when it is rotated. The control knob 83 is then operated to wind up the spring 81 if that has not already been done, and this will operate to take up the slack or exhaust-

ed portion of the web D as it is driven past the pick-up station by the drum C. As the drum is driven by the clock or motor 46 it carries the web D along with it causing it to move beneath the station selector mechanism E, and whenever one of the apertures in the web D passes between the rollers 94 and the drum the rollers will fall therethrough and contact with the surface of the drum 85 thereby completing an electrical circuit which by the aid of the leads 95 will energize the tuning mechanism within the instrument to cause the tuning and retuning of the receiver. Fig. 9 specifically illustrates the cooperation of the drum C and the web D with an element of the station selector mechanism E in completing such a circuit.

As an alternative for the record preparation herein described, the same may be accomplished by an editing agency wherein the controlling webs D, as illustrated in Fig. 11, may be prepared by an agency that has access to advance information of station broadcast over a long range of time, that is to say, a week or more in advance. After such preparation the program editors may distribute or sell the prepared webs to subscribers and others. In other words, the editing agency after studying and analyzing the features of the programs for the various broadcasting stations for the period, may group the same according to the character of the particular feature and arrange them in their time order of occurrence, preparing separate webs for features of a like character. As an example of this, one web might be prepared to tune and retune the instrument so that the evening's program would be made up of dance music, while another would be limited to classical music and still another to educational features etc. Fig. 11 is illustrative of program webs prepared by an editing agency where a prepared web for a program of lectures is designated at 141 as a "Lecture-gram", and for a program of dance music and opera at 142 and 143, which are designated as "Dance-gram" and "Opera-gram" respectively.

The subscriber, in using one of these program webs, needs only place the same over the drum 43, thread it beneath the punch mechanism, adjust the web as to the time scale and close up the panel 22. If the web is long enough and the subscriber wishes to do so, he may attach the exhausted end to the take-up spool 38 as has been described. However, that is not necessary.

In either instance, whether the web be prepared by the radio listener or by an editing agency, when it is trained over the drum 43 and the instrument case is closed there need be given no further attention to it, since the web will be driven by the motor 46 and through the agency of the station selector mechanism E will tune and retune the radio receiver strictly in accordance with the record preparations.

In some instances, a considerable interval of time may elapse between the conclusion of one evening's program that the radio listener has provided for and a subsequent occasion when he desires to control the instrument by the preselector. Under such circumstances a considerable amount of the web D might be unnecessarily wound upon the take-up spool 38, and by reason of that might result in damage to the instrument or injury to the web. Provisions, therefore, have been added to interrupt driving of the web after a reasonable length of time, which includes a spring leaf member 145 disposed relative-

ly near the spool 38 and insulatingly supported from a portion of the frame member B by a bolt or screw 146, and carrying a lead 147. The spring leaf member 145 carries a contact 148 that is engageable with a contact element 149 having a lead 150 that communicates with the common connection or conductor 151 from the drum C to the source of power. An electro-magnet 152 near the top of the casing A and operable upon an armature 153 carried by the spring pressed latch 26 has a conductor 154 joining the multi-conductor cable, before referred to, and has its winding connected to the lead 147.

By reference to the diagram of Fig. 10, it may be seen that as the take-up spool 38 rotates by reason of the energy in the spring 81 to wind up the exhausted end of the web D, the successive layers of web wound upon the cylinder 75 will be sufficient to engage the member 145 and flex it until the circuit is completed between the elements 148 and 149, whereupon the electromagnet 152 is energized and operates the latch 26 to release the panel 22 which now springs outwardly by reason of the force exerted by the flexed contact members 90, thereby releasing the driving engagement between the web D and the drum C. Usually the excess of web D that is wound upon the take-up spool 38 may be re-wound upon the supply spool 35 by manipulation of the control knob 70 in a clockwise direction as the device is viewed from the rear, and there is no real loss or damage to the web D even though a considerable length of time may elapse after the conclusion of a selected program and before the device is again put into use.

Provision is also made for accomplishing a similar result in those instances where the web D is prepared by an editing agency, though the necessity for saving of the web is not there apparent, since the web is usually cut off at or slightly beyond the last web preparation. This is accomplished by connecting one of the elements 90, for instance that one indicated by R, with the electromagnet 152 by a lead 155 joining the lead 147. Since the drum C has electrical communication by the conductor 151 with a source of energy, the element R and drum C form a circuit closer in parallel with the elements 148 and 149 and when closed actuate the release magnet 152 as does the closing of 148 and 149. The release circuit may be established through the element R and drum C, either through the agency of a special preparation of the web or through the passing of the end of the web from under the rollers of the call mechanism, whereby the element 90 opposite the character R on the scale will engage the drum thus completing the circuit through the electromagnet 152 that will operate the latch and thereby interrupt the functioning of the call mechanism. Substantially coincident with this, the roller 94 of the element 90 opposite the scale marking S-S will also engage the drum and through its connection with the set de-energize the same.

While the form of embodiment of the present invention as herein disclosed, constitutes a preferred form, it is to be understood that other forms might be adopted, all coming within the scope of the claims which follow.

What is claimed is as follows:

1. A preselector for radio instruments, com-

prising in combination, a control web, a web actuating drum, station selector mechanism disposed to engage said drum, a take-up spool, and means actuated when a predetermined length of the control web is wound on said spool to release the engagement between the selector mechanism and drum.

2. A preselector for radio instruments, comprising in combination, a control web, a web actuating drum, a case for enclosing said pre-selector and having a movable panel, station selector mechanism carried by the panel and engageable with said drum, a take-up spool for winding up the actuated web, and means cooperating with the spool to release the engagement between said selector mechanism and the drum.

3. A preselector for radio instruments, comprising in combination, a control web, a web actuating drum, a case for enclosing said pre-selector and having a movable panel, station selector mechanism carried by the panel and engageable with said drum, said selector mechanism including means to release the engagement of said mechanism with the drum upon termination of said web.

4. A preselector for radio instruments, comprising in combination, a control web, a web actuating drum, a case for enclosing said pre-selector and having a movable panel, station selector mechanism carried by the panel and engageable with said drum, means to latch said panel in place so as to provide a driving engagement between the drum and selector mechanism for driving said web, and means responsive to the termination of said web to unlatch said panel and relieve the said engagement.

5. A program selector arrangement, adapted for radio receivers, comprising a program control web, a platen extending laterally across said web, a clock operated mechanism for moving said web with respect to the platen, said platen being provided with a plurality of bores, each bore corresponding to a desired station, punch means disposed in alignment with the platen, adapted to cooperate with each bore, for punching apertures in said web according to a predetermined program sequence, and a plurality of station selector circuits each including a switch element in sliding contact with the web whereby registration of an element in one of said apertures results in energization of its corresponding selector circuit.

6. A program selector arrangement, adapted for radio receivers, comprising a program control web, a platen extending laterally across said web, a clock operated drum for moving said web with respect to the platen, said platen being provided with a plurality of bores, each bore corresponding to a desired station, punch means disposed in alignment with the platen, adapted to cooperate with each bore, for punching apertures in said web according to a predetermined program sequence, and a plurality of station selector circuits each including a switch element in sliding contact with a portion of the web which rests on the drum whereby registration of an element in one of said apertures permits contact between said element and drum and results in energization of its corresponding selector circuit.
